UNITED STATES PATENT OFFICE.

ALFRED HALL, OF WINTHROP, MASSACHUSETTS, ASSIGNOR TO HAZEL C. KENDALL, OF BOSTON, MASSACHUSETTS.

GUMMED-STRIP-AFFIXING DEVICE.

1,204,761.

Specification of Letters Patent. Patented Nov. 14, 1916.

Application filed October 18, 1912. Serial No. 726,440.

To all whom it may concern:

Be it known that I, ALFRED HALL, of Winthrop, in the county of Suffolk and State of Massachusetts, have invented certain new and useful Improvements in 5 Gummed-Strip-Affixing Devices, of which the following is a specification.

My invention has reference to improvements in strip feeding and coating or 10 moistening devices.

The main objects of the invention are to provide a device of this character in the form of a tool which may be conveniently held and operated with one hand so that 15 a strip suitably contained therein will be coated or moistened, fed outwardly to the desired length, affixed and severed as desired; which is so constructed that a comparatively long strip may be very easily 20 placed therein; which is provided with means to prevent the strip from coming in contact with the moistening device when not being operated; and which is simple, durable and neat.

25 Other objects of the invention will appear from the following description.

The invention consists in such novel features of construction, operation, and combination of parts as shall hereinafter be more 30 fully described and pointed out in the claims.

Referring to the drawings:—Figure 1 represents a side elevation of a device embodying my invention. Fig. 2 represents 35 a plan view of same. Fig. 3 represents a sectional view on the line 3—3 of Fig. 2. Fig. 4 represents a plan view, partly in section, of a portion of the device. Fig. 5 represents a front end view of the device. Fig. 40 6 represents a sectional view, partly in elevation, on the line 6—6 of Fig. 3. Fig. 7 represents a sectional view on the line 7—7 of Fig. 4. Fig. 8 represents a sectional view, partly in elevation on the line 8—8 45 of Fig. 1.

Like numbers of reference designate corresponding parts throughout.

10 represents a cylindrical strip container, comprising a cup shaped casing 11 and a cover 12 which are preferably made of sheet aluminum. Passing through a central opening in said cover and rigidly secured thereto, is a split pin 13 which engages a 15 socket 14 in a stud or bearing 15. The bearing 15 is rigidly secured at one end 16

to the center of the vertical side 17 of the casing 11 by a screw 18 which passes through an aperture in said casing and is threaded into said end, and is provided with a shoulder 19 which bears against the outer 60 face of said vertical side. The casing 11 is provided with a narrow slot 20 which is formed by cutting a slit longitudinally of said casing and then by bending or rolling the upper edge outwardly, thereby forming 65 a lip 21.

Flush with the lower edge and extending the length of the slot 20 is soldered or otherwise rigidly secured to the casing 11, one 70 end of a water tank 22. Said water tank is preferably made up of a member 23 which is inverted U-shaped in cross section and a member 23^a which is upright U-shaped in cross section, both of which are stamped out of sheet metal, and the vertical sides 75 of said first-mentioned member which is the upper member are soldered to the inner surfaces of the vertical sides of said second mentioned member which is the lower member. The inner end of said upper member 80 is closed and its lower edge is tightly secured to the inner edge of said lower member which forms the end of the tank 22 hereinbefore referred to. The outer end of said lower member bevels outwardly and 85 upwardly to the edge 24 and then bevels inwardly and upwardly to the top of the tank. Near the outer end of the top of said tank and extending transversely is an opening 25 which is sufficiently wide to allow 90 a moistening roll 26, corresponding in length to the width of the inside of the tank, to be passed through. The moistening roll 26 is preferably made of aluminum and is journaled on a pin 27 which extends 95 longitudinally through its center. The pin 27 is journaled near each end in suitable bearings in the vertical sides of the member 24 in such a position that the top of the feed roll extends slightly above the top of the opening 25. On one end of the pin 27 is fixed a thumb nut 28 and on the other end is screwed a thumb nut 29 so that the roll may be easily removed from the casing by removing the nut 29 from said pin and then by sliding said pin from said roll.

Adjacent said roll is a horizontal moistening pad 30 made of felt or other suitable material, which corresponds in length and height to the width and height, respectively,

of the inside of said tank. The moistening pad 30 is held in contact with the roll 26 by a spring actuated plunger 31. Said plunger which is preferably made of German silver, or other non-corrosive material, comprises a perforated U-shaped head 32 which is adjacent the pad 30 and is guided by the side of the tank 22; a rod 33 fixed to the center of said head, the end of which passes through and is guided by an opening in a perforated partition 34 in the tank 22; and a spring 35 on said rod which bears against said head and said partition. The partition 34 is formed by suitably cutting a portion of a vertical side of the member 23 and then bending said portion inwardly, Figs. 3, 4 and 7. The bottom of the tank is provided with an opening 36 closed by a stopper 36a.

20 Journaled on the shoulder 19 of the screw 18 is a tongue 37 which is integral with a casing 38, preferably made of sheet aluminum, which extends over the tank 22 and is so shaped that together with said tank it forms a handle. Said casing 38 has sides 39 portions of which project down over portions of the sides of said tank. The sides 39 are provided with slots 40 which pass over the projecting ends of the pins 27 between 25 the thumb nuts 28 and 29 and the sides of said tank. The outer end of said casing bevels downwardly to the straight edge or severing member 41 which is in a plane slightly below the plane of the top of said tank and extends beyond the end of said casing. Between the sides 39 of said casing is a knurled feed roll 42 which projects through openings in the top of said casing and is supported by a pin 43 the end of which extends through and is adapted to rotate in 30 slots 44 in said sides.

35 On the top of the tank 22 is fastened, at one end by screws 45, a thin sheet of spring metal 46 and the other end bears against 40 the feed roll 42. Said latter end is slotted in such a manner as to form prongs so that a uniform pressure is exerted on the feed roll 42 throughout its length.

45 Preferably, the strip used in this device is first rolled up as is customary, and has a central opening larger in diameter than the diameter of the bearing 15.

50 The strip is placed in the device in the following manner:—First the cover which has a projecting knurled flange 50, is removed from the casing 11 by being pulled outwardly with sufficient force to overcome the friction between the split pin 13 and the socket 14; then the casing 38 is swung upwardly on the shoulder 19 which allows access to the opening 20; in turn the central opening in the strip roll is passed over the bearing 15; then the end of the strip with the surface to be coated or moistened is 55 passed through the opening 20; in turn over

the top of the tank; over the spring plate 46 which is provided with strip guides 47; in turn between the rolls 26 and 42. The cover is then replaced by forcing the split pin 13 into the socket and the casing 38 is swung down into place. As is apparent from the foregoing, the strip roll is supported by the bearing 15 and the remaining portion of the strip is supported by the inner end portion of the top of the tank 22, by the spring plate 46, and by the coating or moistening and feed rolls 26.

60 Water or other fluid which may be admitted through the opening 36 into the tank 22 reaches the pad 30 by passing through the perforations in the partition 34 and the perforation in the plunger head 32.

65 The moistening pad 30 is in close sliding fit with the inside of the tank 22 so that in order for the fluid to reach the moistening roll 26 it must pass through said moistening pad 30, and moisture is applied to said roll by its rotation in contact with said pad. Said moistening pad serves as a stopper to prevent the fluid from leaking out of the 70 tank 22 through the opening 25 when the device is tipped.

75 The strip may be fed and coated or moistened in the following manner:—First the device is grasped with one hand by the handle formed by the casing 38 and the tank 22 in such a manner that the thumb may be pressed downwardly on the feed roll 42 and at the same time be moved so as to rotate said feed roll in the direction of the arrow 80 shown in Fig. 3. Normally the spring plate 46 forces the portion of the strip which is above the moistening roll 26 away from said moistening roll, but by the pressure of the thumb on the feed roll 42 the action of the 85 spring is overcome and said portion of the strip is forced down upon said moistening roll. By rotating said feed roll as hereinbefore indicated the strip is forced to move outwardly by the frictional contact between 90 said roll and said strip which causes the moistening roll 25 to rotate and said moistening roll is suitably knurled so that a sufficient amount of moisture is taken from the 95 moistening pad 30 and carried by the knurled surface of said moistening roll to moisten the under surface of said strip.

100 The strip may be affixed by continually pressing the straight edge 41 against the top of said strip as it is being fed outwardly. After a small 105 portion of the strip has been affixed it is only necessary to slightly press the thumb against the top of the roll 42, to press said straight edge against the top of said strip and to move either the device or the object 110 on which the strip is being affixed away from the other, which does away with the necessity of moving the thumb. When the desired length of the strip has been affixed it may be severed by tearing said strip on 115

said straight edge while pressing the thumb firmly against said feed roll. As hereinbefore stated, the strip is thrown out of contact with said moistening roll when pressure is released from the feed roll 42 so that it will not stick to said moistening roll. The spring plate 46 has a ratchet effect on the knurled surface of said feed roll through the strip, which tends to prevent said feed roll from rotating in the opposite direction to that hereinbefore indicated. This is advantageous in that if said feed roll did rotate in said opposite direction the strip might be thrown out from between said feed roll and said moistening roll.

Having thus described my invention I claim as new and desire to secure by Letters Patent:—

1. In an article of the character described the combination of a strip container, a tank fixed to said strip container, a casing pivoted on said strip container, said tank and casing of suitable shape to serve as a handle, with means adapted to convey moisture from said tank to a strip fed from said strip container.

2. In an article of the character described a strip container comprising a casing provided with a centrally located roll support bearing, a socket in said bearing, a cover adapted to close said casing, a split pin fixed at one end to the center of said cover and adapted to be forced into said socket, in combination with a finger operated strip feeding and moistening means.

3. An article of the character described comprising a strip roll container, a tank fixed at one end to said container, a moistening roll journaled on a pin which passes through the sides of said tank, a casing pivoted at one end to the center of a side of said container and so shaped that together with said tank the casing forms a handle, a strip severer on the other end of said casing, a finger operated feed roll mounted on a pin which passes through and is guided by slots in said casing, said feed roll being in such a position and so constructed as to be adapted to cooperate with said moistening roll to feed a strip between said rolls.

4. In an article of the character described

a cylindrical container, a strip roll bearing fixed at one end to the center of the vertical side of said container by a screw, a socket 55 in the other end of said bearing, a split pin engaging said socket which is fixed to a cover adapted to close said container, a longitudinal slot in said casing, a tank fixed to said container, a moistening roll journaled on a pin which passes through two sides of said tank, a pad adjacent to said moistening roll, a spring actuated plunger pressing said pad against said roll, a casing pivoted on a shoulder on said screw, a finger operated feed roll mounted on a pin which extends through and is guided by slots in the side of said casing, said casing and tank of suitable shape and size to serve as a handle.

5. In an article of the character described, the combination, of means for supporting a strip, a tank beneath said supporting means adapted to receive a liquid, a moistening roller at one end of said tank and projecting slightly above the top thereof, means above said tank for supporting a feed roller, said latter means and said tank of suitable form and said feed roller so positioned that said means and said tank 80 may be conveniently grasped by a hand of the operator, and said feed roller rotated by movement of the thumb thereof to feed the said strip over said moistening roller.

6. In an article of the character described, the combination, of an elongated tank adapted to receive a liquid, means on the top of said tank for supporting a strip, means at the forward end of said tank for conveying moisture from said tank to the 90 said strip, means above said tank for supporting a feed roller adapted to be rotated to feed the said strip over said moistening means, said supporting means adapted to be swung away from said tank on a pivot 95 at the rear thereof, and said supporting means and said tank coöperating to form a handle to operate the article.

In testimony whereof I have affixed my signature, in presence of two witnesses.

ALFRED HALL.
